UNITED STATES PATENT OFFICE

155,287

DESIGN FOR A HACKING TOOL

Albert Henry Hawes, Erdington, Birmingham, England, assignor to Kwikform Limited, Birmingham, England

Application December 30, 1947, Serial No. 143,458
In Great Britain November 15, 1945
Section 1, Public Law 690, August 8, 1946

Term of patent 14 years

(Cl. D54—13)

To all whom it may concern:

Be it known that I, Albert Henry Hawes, a subject of the King of Great Britain, residing at Erdington, Birmingham, county of Warwick, England, have invented a new, original, and ornamental Design for a Hacking Tool, of which the following is a specification, reference being had to the accompanying drawing, forming part thereof.

Figure 1 is a perspective view of a hacking tool, embodying my new design.

Figure 2 is a perspective view from the other side thereof.

I claim:
The ornamental design for a hacking tool, as shown.

ALBERT HENRY HAWES.
